UNITED STATES PATENT OFFICE.

CHARLES S. ASH, OF BUFFALO, NEW YORK, ASSIGNOR, BY MESNE ASSIGNMENTS, TO
WIRE WHEEL CORPORATION OF AMERICA.

PAINT-BELL.

1,380,761.

Specification of Letters Patent. Patented June 7, 1921.

Application filed July 14, 1916. Serial No. 109,279.

To all whom it may concern:

Be it known that I, CHARLES S. ASH, a citizen of the United States, residing at Buffalo, in the county of Erie and State of New York, have invented certain new and useful Improvements in Paint-Bells, of which the following is a full, clear, and exact description, such as will enable others skilled in the art to which it appertains to make and use 10 the same.

This invention relates to improved means for and method of manufacturing wire-spoked vehicle wheels and the like.

One of the objects of the invention is to 15 provide a practical and simplified device for expediting the application of a paint or enamel coating to the external surface of the parts of a wire-spoked automobile wheel.

A further object is to provide an improved device for the purpose mentioned, 20 wherein the painting operation can be effected at a minimum labor and material cost.

Other objects and advantages will be in 25 part noted hereinafter in connection with the following description of the accompanying drawing, which illustrates a typical embodiment of the invention, and wherein—

Figure 1 is a front elevational view.

Fig. 2 is a side elevational view showing 30 in dotted lines, a wheel mounted in position.

Fig. 3 is a vertical section of the wheel and standard.

Referring more particularly to the drawing, there is shown a horizontally disposed, 35 funnel-shaped housing 1 mounted upon a rigid cast standard 2 and connected at its rear end 3, of reduced diameter, by a flue 4, to a vertical air shaft 5. A blast fan 6 is positioned at the bottom of the air shaft 5 40 to create a draft of current from the open front end 7 of the housing rearwardly through the flue 4 and vertically through the shaft 5 to a suitable exhaust. The fan 6, as illustrated, is driven by a unit motor 8, though it will be understood that other driving means may be provided, if desired. 45 A check valve 9 is also preferably located in the shaft 5 to regulate the air current independently of the fan 6.

There is provided within the housing a 50 vertical standard 10 secured above the front upright of the supporting standard 2 and having an offset oblique extremity 11 which carries a member rotatably mounted to turn 55 freely on standard 10 and shaped as a wheel

hub to receive the wheel unit 12 constituted by a hub shell 13, interlaced wire spokes 14 and rim 15.

In operation, a wheel to be painted or enameled is positioned upon the dummy hub 60 11 and rotated or spun about the hub axis by the operator, who then applies a coating of the paint or enamel through a pressure atomizer or sprayer. In this operation the spray is directed inwardly of the housing so 65 that the waste is carried by the air draft rearwardly. The air further expedites the drying. After the paint has been properly applied with the wheel rotating in one direction, the operator then spins the latter in 70 the opposite direction and applies the spray to the reverse or uncoated area. The wheel may then be turned about the axis of the standard 10 and spun to apply the paint to 75 the rear of the wheel, so that the paint or enamel spray will reach and cover uniformly all the exposed surfaces.

There is also preferably provided a reflector 16 secured to the top of the housing 1 and projecting obliquely upward over the 80 open end. Suitable incandescent lamps or other illuminants are placed in the reflector 16 to cast rays on the device mounted in the housing to which the paint is to be applied.

The device described is particularly 85 advantageous in the manufacture of wire-spoked vehicle wheels, wherein a relatively great number of spokes are interlaced between the hub and rim and where the spokes cross at a plurality of points and afford 90 relatively acute and inaccessible corners or areas. It will be readily understood, however, that the device is adapted for use in painting various parts which are capable 95 of mounting, preferably rotatably, on a standard, such as 10, in the housing.

As many changes could be made in the above construction and many apparently 100 widely different embodiments of this invention could be made without departing from the scope thereof, it is intended that all matter contained in the above description or shown in the accompanying drawings shall be interpreted as illustrative and not in a limiting sense.

It will be observed that the dummy hub 11 is arranged with its axis at an inclination to a horizontal plane, so that the wheel will rotate in an inclined plane. The wheel, therefore, need only be slipped onto the 110

dummy hub, whereon it will be maintained by gravity during its revolution. No fastening means of any character are needed and at all times the wheel may be quickly removed 5 by slipping it off from the dummy hub. The inclination shown in the drawing is that considered best for a quick and even application of the paint spray and such as will enable the workman to readily observe the 10 progress of the work being done, notwithstanding the fact that the wheel is held within an encircling hood. One side of the wheel having been covered, the workman, by simply turning the wheel about the 15 vertical axis of the standard 10, can expose the opposite side of the wheel to the action of the spray, and this can be done without lifting the wheel from its dummy hub.

Having described my invention, what I 20 claim as new and desire to secure by Letters Patent is:

1. In apparatus for painting wheels, the combination of a housing, means for insur-

ing a draft of air therethrough, and an upwardly inclined support within the housing 25 on which the wheel to be painted rests by gravity and about which it is freely rotatable, said inclined support being turnable about a vertical axis, substantially as described.

2. In combination a housing air draft producing means, a vertical supporting member within the housing having an upwardly inclined offset portion at its upper 30 end and a dummy hub turnable on said offset portion, said inclined offset portion with its hub being turnable to different portions about the axis of the vertical supporting member.

In testimony whereof I affix my signature 40 in the presence of two witnesses.

CHARLES S. ASH.
